ARNOLD ZUKOR AND HANS IRMSCHER, OF NEW YORK, N. Y.

COMBINED DOOR FASTENER AND ALARM.

Application filed November 23, 1926. Serial No. 150,275.

The present invention relates to improvements in combined door fasteners and alarms, and has for its main object to provide a latch permitting of a limited opening movement 5 of the door and to combine the same with an alarm device, which is set in operation when the door is swung toward opening movement as far as the latch permits.

Another object of the invention is to provide 10 a device of the character described which embraces a strong, durable and efficient fastener arrangement provided with an appropriate alarm feature.

A further object of the invention is to provide 15 a device which is simple in construction and capable of manufacture on a commercial scale, or in other words one which is not so difficult to produce as to be beyond the reasonable cost of such a contrivance.

20 With these and other objects in view, which will more fully appear as the nature of the invention is better understood, the same consists in the combination, arrangement and construction of parts hereinafter described, 25 pointed out in the appended claim and illustrated in the accompanying drawings, it being understood that many changes may be made in the size and proportion of the several parts and details of construction within the 30 scope of the appended claim, without departing from the spirit or sacrificing any of the advantages of the invention.

One of the many possible embodiments of 35 the invention is illustrated in the accompanying drawings, in which:—

Figure 1 is a top plan view of a device constructed in accordance with the present invention, applied to the door and door jamb, the latter two elements being shown in section; Fig. 2 is a side elevation of the keeper associated with the latch bolt, in combination with the alarm device; and Fig. 3 is a front elevation of the latch casing and latch bolt.

40 In the drawings, the numeral 10 indicates one of the side posts of a door frame and the numeral 11 a door, hinged in the usual manner to the opposite side post of the door frame. A lock of any suitable construction, 45 not shown, may be provided for securing the door both from the inside and outside. For the purpose of securing the door from the inside against forcible entry, a sliding latch bolt 12 is mounted within a latch casing 13, the latter being fastened by screws 14, or otherwise, to the inner face of the door

adjacent its free, vertical edge 15. The latch casing is provided with a longitudinal slot 16, having in each of its ends notches 17, with which is adapted to co-operate a knob 18 on 50 the latch bolt, for holding the latter in its open and closing positions. The bolt 12 cooperates with a keeper 19, the latter being in the form of a bracket provided with two flanges 20 and 21, which extend at right angles to one another. The flange 20 abuts against the inner face 22 of the side member 10 of the door frame, while the flange 21 is disposed within a mortise 23 in that side face of the frame member 10 which is adjacent the 55 free vertical edge 15 of the door 11. In the bracket is provided a horizontal slot 24, which extends at right angles to the longitudinal axis of the bolt 12 when the door is in its closed position. The width of the slot 60 is of a size to accommodate the bolt 12, while its length exceeds considerably the size of the diameter of said bolt. The inner edge 25 of the slot is so disposed that it permits the bolt to be thrown to securing position when the door is closed, and the slot is of such length 65 that it permits the door to be partly opened with the bolt in its projected position. On the bracket is mounted by screws 26, or otherwise, the base of a rotary bell 27, containing a 70 suitable mechanism, such as a hammer actuating device therefor, whereby, when the bell is released and allowed to be revolved by the usual spring, the bell is sounded. On the bell base is mounted a plunger trip 28, which, 75 when pressed toward the center of the bell, releases the mechanism and causes the bell to be sounded. This plunger trip is disposed at right angles to the inner face 22 of the side member 10 of the door frame, its head 29 80 facing the inner face of said side frame member and projecting toward the latter to a distance that it comes into contact with the outer end of the bolt 12 before the latter strikes against the outer edge 30 of the slot 24. In 85 other words, the head 29 is in the path of the bolt 12 when the door is swung toward opening position with the bolt projected into the slot 24.

90 The operation of the combined door fastener and alarm is as follows: When the door is to be secured against forcible entry, the bolt 12 is projected into the slot 24 in the bracket 19 and secured in such position by seating the knob 18 in one of the inner 95 notches 17 in the bolt casing. If then the door is opened to a slight degree, the outer 100

105

110

end of the latch bolt abuts against the outer edge 30 of the slot 24 in the bracket 19, preventing the door from being opened further. At the same time the bolt 12 strikes against 5 the plunger trip 28, whereby the bell is at once operated, giving an alarm.

What we claim is:

The combination with a door frame and a door hinged thereto, of a longitudinally 10 shiftable latch bolt on said door, a keeper on said frame provided with a horizontal slot through which said bolt is adapted to be projected, said bolt engaging in its projected position the inner edge of said slot when said 15 door is in its closed position, said slot per-

mitting of a limited opening of said door when said bolt is projected into said slot, a bell mounted upon said keeper, and releasing means for said bell including a shiftable plunger trip provided with a head, said head 20 facing the inner face of said door frame and projecting beyond the outer edge of said slot whereby said bolt is adapted to contact with said head before it strikes against the outer edge of said slot.

Signed at New York, in the county of New York, and State of New York, this 5th day of November, A. D. 1926.

ARNOLD ZUKOR.
HANS IRMSCHER.
